UNITED STATES PATENT OFFICE.

FRANK S. WASHBURN, OF NASHVILLE, TENNESSEE, ASSIGNOR TO GOODMAN MANUFACTURING COMPANY, OF CHICAGO, ILLINOIS, A CORPORATION OF ILLINOIS.

MINING-MACHINE.

1,256,619.

Specification of Letters Patent. Patented Feb. 19, 1918.

Application filed July 21, 1911. Serial No. 639,712.

To all whom it may concern:

Be it known that I, FRANK S. WASHBURN, a citizen of the United States, residing at Nashville, in the county of Davidson and State of Tennessee, have invented a certain new and useful Improvement in Mining-Machines, of which the following is a specification.

This invention relates to mining machines, and has for its object to provide a new and improved machine of this description.

The invention is illustrated in the accompanying drawings, wherein—

Figure 1 is a plan view showing a machine embodying the invention;

Fig. 2 is an end view of the machine illustrated in Fig. 1.

Like numerals refer to like parts throughout the several figures.

Referring now to the drawings, I have illustrated a mining machine having a frame 1 upon which is mounted a motor 2. A cutting device projects from said frame. As herein shown this cutting device comprises a cutter arm 3, about which moves a chain 4 actuated by the motor, said chain carrying a series of cutters 5 which engage the material to be acted upon. A suitable feeding mechanism is provided for feeding the machine forward to bring the cutting device into proper relation to the material to be acted upon. This feeding mechanism comprises a flexible power transmitting device wound about a drum 7 and engaging a pulley 8 connected with the frame of the machine. The drum 7 is rotated by the gear 9 which engages teeth 10 on the inner face of the drum. The gear 9 is connected with shaft 11, said shaft being operatively connected with the motor 2. A clutch 12 is preferably provided so that the feeding mechanism may be disconnected from the motor. In view of the fact that the cutting device projects from the front end of the machine, it is found that when the feeding mechanism is brought into action the resistance of the face of the material to be acted upon coming upon the cutters tends to cause the rear end of the machine to move forward more rapidly than the front end, so that the machine takes an inclined position with the cutting device to the rear. Some suitable retarding device is provided for preventing the too rapid forward movement of the rear end of the machine. In

the construction shown this retarding device consists of a flexible power transmitting device 13, connected with a fixed device 14 at a suitable distance from the machine and coiled about a vertical post 15 carried on the frame of the machine. The free end 16 of this flexible power transmitting device is held by the operator of the machine, so that it can be held tight or loosened up as required to hold the rear end of the machine back sufficiently to secure the proper forward feeding movement. Some suitable means is provided for preventing the coils of the power transmitting device on the post 15 from coming into contact with each other, for otherwise the flexible power transmitting device would soon be destroyed, and, in addition, the control thereof would be more difficult and the device would not be so responsive to the variations in power applied to the loose end. As herein shown the post 15 is provided with a spiral groove 17 which extends thereabout, and which is arranged so that the convolutions thereof are of proper size and shape to receive the coils of the flexible power transmitting device, and prevent undue pressure between the several coils thereof.

The use and operation of my invention are as follows:

When the machine is being used the flexible power transmitting device 13 is coiled a sufficient number of times about the post 15 and the loose end 16 thereof is grasped by the operator. The machine is fed forward by the rotation of the drum 7, and is retarded by the flexible power transmitting device 13. If the rear end of the machine begins to lag behind because of the retarding device, the operator slacks up on the loose end 16 and permits the flexible power transmitting device to slide on the post 15, thus relieving the pressure and permitting the rear end of the machine to be moved forward by the feeding mechanism. If, on the other hand, the rear end of the machine is moved forward to too great an extent, the operator pulls upon the loose end 16 of the flexible power transmitting device 13 so as to prevent the slipping movement thereof on the post 15, thus causing the feeding mechanism to gradually move the cutter end of the machine forward so as to bring the machine into proper position.

It will thus be seen that by means of this construction the feeding of the machine can be properly controlled by the operator without undue injury to the controlling mechanism, and that the controlling mechanism is responsive and easily controlled.

It will be noted that in this construction the flexible power transmitting device 13 which passes around the post 15 and which 10 is connected to a fixed part, is in fact connected with the frame of the machine above the plane of the cutter and hence the pull of this flexible power transmitting device in holding back the machine tends to tip the 15 machine so as to cause the cutter to rise as the machine passes along the face of the coal. This tilting of the machine and the cutter is aggravated when a smooth post 15 is used, by the fact that the coils of the rope 20 slide up toward the top, thus increasing the leverage and increasing the tipping effect of the power transmitting device 13. This tilting of the cutter causes the cutter to move upwardly on an incline and form an inclined 25 cut as the machine passes along the face of the coal. This moving up of the cutter must be prevented, for if not prevented, the cut no longer remains at the bottom of the seam but on the other hand gradually moves up 30 above the bottom of the seam, leaving a layer of coal below the cut, and this coal is either wasted or removed at additional expense. Another evil produced by the moving up of the cutter is that it carries the machine with 35 it, tending to raise the motor off the floor and in many cases tending to crowd the motor against the roof and interfere with its operation. This also puts severe strains upon the machine. Another evil is that 40 when the machine reaches the roof of the mine it must be stopped, because the cut cannot be proceeded with. The machine must then be withdrawn and a new cut begun. One of the objects of the present device is to 45 avoid this evil. It will be noted that in this device, as the machine moves across the face of the coal the flexible power transmitting device 13 is paid out from the post 15. It will further be noted that that portion that 50 is being paid out is at the bottom of the post, and that means are provided for keeping it at the bottom of the post at all times and thereby reducing the tilting lever arm to a minimum and keeping at this minimum during 55 the entire operation of the machine. This is clearly illustrated, for example, in Fig. 2. The frame 1 of the machine, as illustrated in this figure, is preferably just of sufficient height to give proper space for the cutter chain and a proper thickness of 60 metal at the bottom and top to secure a strong structure and the paying out portion of the rope 13, that is the portion that leaves the post, is located and held at the bottom of 65 the post and very near the center line of the

chain, thus reducing this tilting lever arm to a minimum and the grooved construction holds it at this minimum at all times.

I claim:

1. A mining machine comprising a frame, 70 a cutting device projecting therefrom, a motor mounted on said frame, a feeding mechanism for feeding the cutting device toward the material to be acted upon, a non-rotating vertical post connected with said frame, 75 a spiral groove on said vertical post, a flexible power transmitting device arranged about said vertical post to form coils which fit into said spiral groove, said coils having a sliding engagement with said post when 80 the machine is in operation, the end of the flexible power transmitting device being free so as to be grasped by the operator, said flexible power transmitting device connected with a fixed part at a distance from 85 the machine, the point of application of the retarding force being relatively to the rear of the point of application of the feeding force.

2. A mining machine comprising a frame, 90 a cutting device projecting therefrom, a motor mounted on said frame, a feeding mechanism for feeding the cutting device toward the material to be acted upon, comprising a flexible power transmitting device connected with a fixed part at a distance from 95 the machine and means for winding up said flexible power transmitting device, a retarding device for retarding the movement of the rear end of the machine in response to 100 the feeding mechanism, comprising a second flexible power transmitting device having one end connected with a fixed part at a distance from the machine, a non-rotating part on the machine about which said sec- 105 ond power transmitting device is coiled, and having a sliding engagement therewith when the machine is in operation, the loose end thereof projecting from the machine so as to be grasped by the operator, said part 110 being in off-set relation to the point where the flexible power transmitting device of the feeding mechanism leaves the machine, said non-rotating part about which the sec- 115 ond power transmitting device is coiled being provided with a spiral groove whereby the second power transmitting device pays off from the fixed part at a fixed point near the bottom thereof at all times.

3. A mining machine comprising a frame, 120 a cutting device projecting therefrom, a motor mounted on said frame, a feeding mechanism for feeding the cutting device toward the material to be acted upon, comprising a flexible power transmitting device connected with a fixed part at a distance from 125 the machine and means for winding up said flexible power transmitting device, a retarding device for retarding the movement of the rear end of the machine in response to the 130

- feeding mechanism, comprising a second flexible power transmitting device having one end connected with a fixed part at a distance from the machine, a non-rotating part 5 on the machine about which said second power transmitting device is coiled, and having a sliding engagement therewith when the machine is in operation, the loose end thereof projecting from the machine so 10 as to be grasped by the operator, said part being in off-set relation to the point where the flexible power transmitting device of the feeding mechanism leaves the machine, and means for relieving the pressure between 15 the coils of said second flexible power transmitting device so that it may be easily paid out as the machine moves along and for maintaining a constant distance between the center line of the cutting device and the 20 point where said second power transmitting device pays off from the non-rotating part, said means comprising said non-rotating part, said non-rotating part having a spiral groove extending thereabout, the second 25 flexible power transmitting device adapted to be wound about the post in said groove to form coils which fit in said spiral groove.
4. A mining machine comprising a frame, a cutting device projecting therefrom, a motor mounted on said frame, a feeding mechanism for feeding the cutting device toward the material to be acted upon comprising a flexible power transmitting device connected with a fixed part at a distance from 30 the machine and means for winding up said flexible power transmitting device, a retarding device for retarding the movement of the rear end of the machine in response to the feeding mechanism comprising a second 35 flexible power transmitting device, having one end connected with a fixed part at a distance from the machine, the two said fixed parts being in offset relation, a vertical non-rotating post fixed to the machine, said post 40 decreasing in diameter from the bottom toward the top and having a spiral groove extending therearound so as to form a series of convolutions, said spiral groove substantially uniform in depth throughout its entire length, said second power transmitting device coiled about said post, the coils being received in such spiral groove and having a sliding engagement therewith when the machine is in operation, the loose end thereof 45 projecting from the machine so as to be grasped by the operator, the other end of the second flexible power transmitting device paying off from said post at the lower end of said groove.
